UNITED STATES PATENT OFFICE.

ALVIN C. McCORD, OF CHICAGO, ILLINOIS.

DRAFT-RIGGING FOR CARS.

1,149,662.

Specification of Letters Patent. Patented Aug. 10, 1915.

Application filed April 23, 1914. Serial No. 833,891.

To all whom it may concern:

Be it known that I, ALVIN C. McCORD, a citizen of the United States, residing at Chicago, in the county of Cook and State 5 of Illinois, have invented certain new and useful Improvements in Draft-Rigging for Cars; and I do hereby declare the following to be a full, clear, and exact description of the invention, such as will enable 10 others skilled in the art to which it appertains to make and use the same.

My invention relates to draft rigging for cars and provides an extremely simple and highly efficient laterally flexible connection 15 between the coupler and the draft gear or rigging.

Generally stated, the invention consists of the novel devices and combinations of devices hereinafter described and defined in 20 the claims.

Particularly, the present invention relates to draft gear or rigging wherein the coupler is connected, by means of a key, to arms, links, yoke or other suitable part of 25 the draft gear. From this statement it will be understood that my invention is applicable to various different types of draft gear or rigging wherein a coupler connecting key is employed.

80 In the accompanying drawings I have illustrated my present invention as incorporated in or applied to a draft rigging of the type disclosed and claimed in my pending application, Serial Number 391,308, filed 85 September 6, 1907, and entitled "Draft rigging for cars," and which application illustrates the preferred form of a differential draft gear that is broadly disclosed and broadly claimed in my Patent 763,998, 40 issued of date, July 5th, 1904, and entitled "Draft rigging for cars".

Describing now in detail the invention as embodied in the preferred form of draft rigging, Figure 1 is a view chiefly in plan 45 but with some parts in horizontal section and with some parts broken away, showing the said draft rigging; and Fig. 2 is a view chiefly in vertical section taken centrally through the draft rigging, but with some 50 parts shown in full and with some parts broken away.

The numeral 1 indicates the draft or center sills of the car. To the rear portions of these sills 1 are rigidly secured heavy 55 rear follower stops 2. To the forward portion of said sills are rigidly secured front

follower stops in the form of heavy metallic plates 3 that are provided with long horizontally extended slots 4 that are co-incident with slots 5 in the draft sills 1. 60

The coupler bar 6, at its rear end, carries a heavy transversely extended key 7 that loosely fits a seat formed therein, and the ends of which project through the slots 4-5 and are adapted to slide both forwardly and rearwardly in said slots, from the normal position shown in the drawings. 65

The body or casing of the draft rigging is indicated as an entirety by the numeral 8, that is provided with laterally projecting follower lugs 10 that normally engage the rear stop lugs 2, and afford one form of rear follower. At its front end the casing 8 is provided with laterally spaced forwardly projecting draft arms 13 that are provided with longitudinal slots 14, through which the key 7 is passed. The slots 14 are of such length and are so disposed that in the normal position of the parts shown in 70 the drawings, the forward extremities thereof, engage with the forward edge of the key 7, and the rear extremities of said slots, as shown, terminate in line with the rear 75 extremities of the slots 4-5. 80

The front follower 15 normally engages the rear end of the coupler bar 6 and the rear ends of the front follower stops or draft lug plates 3, and it is provided with 85 passages through which the draft arms 13 work freely.

The spring cap 17 serves as a secondary or intermediate follower and is mounted to slide within the casing 8. The draft gear spring 12 is located within the casing 8 and 90 is compressed between the cap 17 and the inner end of the said casing 8.

Cam acting differential levers 18 and 19 are directly interposed between the front follower 15 and the cap or intermediate follower 17. These levers are placed within 100 and centrally of the front portion of the casing 8 and are pivotally connected thereto, respectively at 18^a and 19^a. The draft gear construction so far specifically described, is 105 identical or substantially identical with that disclosed in my said pending application above identified.

To provide for lateral flexibility or oscillatory swinging movements of the coupler 110 in respect to the draft rigging, the key 7 is provided with a curved edge 20 and a sup-

plemental key 21 having a reversely formed curved surface fitting the said curved surface 20, is inserted into the key slot of the coupler bar and is pressed between the said 5 curved surface 20 and the solid inner end portion of the said coupler bar. The surface 20 on the key 7 is preferably made convex and projected rearward or inward and the engaging surface of the supplemental 10 key 21 is made concave.

The tension of the spring 12 acting through the rigging, normally holds the supplemental key 21 tightly pressed between the key 7 and inner end of the coupler 15 bar, so that it will not be accidentally misplaced; and furthermore, the pressure exerted by the spring 12 yieldingly presses the front follower 15 against the flat inner end of the coupler bar and yieldingly holds the 20 same in a centered normal position. However, in traveling curves, the coupler can freely swing out of center to adapt itself to the line of strain, (see, for example, dotted lines in Fig. 2). Under such lateral swing- 25 ing movement of the coupler bar, the co-operating curved surfaces of the main and supplemental keys move, one on the other and afford the desired pivot or fulcrum. This construction, therefore, affords an ex- 30 tremely simple and highly efficient laterally flexible connection between the draw bar and draft rigging, and furthermore, permits the coupler bar to be very quickly connected to or disconnected from the draft rigging.

35 It is very desirable that the supplemental wedge 21 should be an independent or individual element, but from a broad point of view, it affords a curved surface movable with the coupler bar and which engages the 40 coöperating curved surface on the key.

From what has been said, it is obvious that my present invention may be applied to or incorporated with any form of draft gear or rigging wherein the coupler bar is 45 connected by a key to a member or members that move with one of the followers.

What I claim is:

1. The combination with a draft rigging and a coupler bar, of a horizontally extended key connecting said bar to one of the 50 movable elements of said draft rigging, said key having a longitudinally curved surface

adapting the said coupler bar to oscillate laterally.

2. The combination with a draft rigging 55 and a coupler bar, of a horizontally extended key connecting said bar to one of the movable elements of said rigging, said key having a longitudinally curved edge engaging a curved surface carried by said draw 60 bar and affording a pivot adapting said draw bar to oscillate laterally.

3. The combination with a draft rigging and a coupler bar; of a key connecting said draw bar to one of the movable elements of 65 said rigging, a supplemental key interposed between the first noted key and said coupler bar, the said two keys having engaging curved surfaces affording a pivot adapting said coupler bar to oscillate laterally. 70

4. The combination with a draft rigging comprising follower stops, coöperating followers, a cushioning device interposed between said followers, and laterally spaced slotted arms connected to the inner follower, 75 of a coupler bar extended between said slotted arms and engageable with the front follower, and a key extended through said slotted arms and through said coupler bar and having a curved surface engageable with a 80 curved surface carried by said draw bar and affording a pivot adapting said draw bar to oscillate laterally.

5. The combination with a draft rigging comprising follower stops, coöperating fol- 85 lowers, a cushioning device interposed be- between said followers, and laterally spaced slotted arms connected to the inner follower, of a coupler bar extended between said slot- 90 ted arms and engageable with the front fol- lower, a key extended through said slotted arms and through said draw bar, and a sup- plemental key interposed between the first noted key and the inner end of said coupler bar, the said keys having curved engaging 95 surfaces affording a pivot adapting said coupler bar to oscillate laterally.

In testimony whereof I affix my signature in presence of two witnesses.

ALVIN C. McCORD.
